UNITED STATES PATENT OFFICE.

FRANK HEILOS, OF PARIS, ARKANSAS, ASSIGNOR OF ONE-HALF TO A. A. ZIMMER, OF PARIS, ARKANSAS.

WIRE-STRETCHER.

1,101,797.

Specification of Letters Patent. Patented June 30, 1914.

Application filed December 1, 1913. Serial No. 804,003.

To all whom it may concern:

Be it known that I, FRANK HEILOS, a citizen of the United States, residing at Paris, in the county of Logan, State of Arkansas, have invented certain new and useful Improvements in Wire-Stretchers; and I do hereby declare the following to be a full, clear, and exact description of the invention, such as will enable others skilled 10 in the art to which it appertains to make and use the same.

This invention relates to improvements in wire stretchers.

One object of the invention is to provide a 15 simple device of this character by means of which single wires, woven wire, or barbed wire may be stretched from post to post or slack taken up midway of the length of the wire.

20 Other objects and advantages will be apparent from the following description, when taken in connection with the accompanying drawings.

In the drawings: Figure 1 is an elevation 25 of the improved wire stretching tool. Fig. 2 is an edge view of one of the bars forming a part of the invention. Fig. 3 is a longitudinal sectional view on the line 3—3 of Fig. 1. Fig. 4 is a detail view showing the 30 portions of the tool in operation when taking up slack in a wire.

Referring particularly to the accompanying drawing, A and B represent, respectively, two bars which form parts of the 35 wire stretcher. Each of the bars has a cut away portion at its outer end which results in a shoulder 10, this shoulder having a curved and serrated face. Pivoted in the cut away portions of the bars are the jaw 40 members 11 and 11' each of which has an oppositely curved and serrated face 12 disposed adjacent the face of the shoulder 10. The faces of the shoulders and jaws are arranged eccentrically with respect to each 45 other, and coöperate to clamp a fence wire therebetween, as clearly shown in Figs. 1 and 4. The outer end of the jaw member 11 is provided with a hook 13 on which is arranged to be engaged a link of a chain 14, 50 this chain being stretched between the members 11 and 11' as shown and having another of its links engaged on a hook 15 car-

ried by the outer end of the jaw member 11'. Between the hook 13 and the pivot point of the member 11 is pivotally mounted a loop 55 16, and engaged in the loop, is one link of a second chain 17. The chain 17 extends to the jaw member 11' where another one of its links is engaged on a hook 18 carried by the said jaw member 11'. At the opposite end 60 of each of the shanks of the members A and B, is a hook 19, a chain 20 being arranged to be engaged thereon to hold the shanks in proper operative position when a wire is stretched between the clamps. 65

When the device is to be used to stretch a single wire, the chain 17 is disengaged from the member B and the chain 14 disengaged from the member A. The member A is then used alone. The chain 17 is then passed 70 around a post, the outer end of the chain being engaged with the hook 13 and the member A. The fence wire is then engaged between the jaws of the member. By rocking the member A on the fence post as a pivot, 75 the jaws will grip the wire and draw the same into taut condition. It will of course be understood that the member B may be used alone and operated in the same manner as the member A. 80

When the device is used to take up slack between the posts, both of the members A and B are used, the chains being then engaged as shown in Fig. 1. The fence wire is passed between the serrated faces of the 85 shoulders 10 and the jaw members 11 and 11' and by drawing the shanks of the members A and B together, the fence wire will be drawn from both adjacent posts, so that a loop will be formed between the members, 90 as shown at 21 in Figs. 1 and 4. It will be noted that the chain at the outer ends of the jaw members 11 and 11' holds the said members rigidly in position, and forms the fulcrums of the levers. The chain 20 holds the 95 shanks together so that the loop 21 can be twisted or the wire cut and spliced at this point.

What is claimed is:

In a wire stretcher, a pair of lever members each having a curved shoulder provided with a serrated face, a member eccentrically pivoted on each of the lever members and provided with a curved serrated face for 100

wire gripping coöperation with the serrated face of the lever member, hooks carried by the pivoted members, and chains extending between the pivoted members and adjustably engaged with the hooks for spacing the members apart and forming the fulcrums of the lever members.

In testimony whereof I affix my signature in the presence of two witnesses.

FRANK (X) HEILOS.
